BOAT FENDER

Dixon P. Downey, Franklin, Pa.

Application February 17, 1956, Serial No. 566,276

6 Claims. (Cl. 114—219)

Many boat fenders have been developed to protect the hulls of boats and ships. The most common type is a tubular bag or casing of woven material which is stuffed with a shock-absorbing material such as foam rubber or fabric. Such fenders possess a limited useful life since the outer woven fabric is quite susceptible to rotting and splitting and the inner stuffing material is thus lost. Furthermore, such fenders are weighty and become water-logged and do not float readily. Other known fenders have air chambers of the pneumatic type. Such devices are also of limited durability.

This invention avoids the difficulties of the prior art. The present fender is constructed of lightweight, flexible, durable material which avoids the tendency to split. The plastic materials of construction are elastic and effectively cushion blows against boat or ship hulls and at the same time provide a corrosion-proof and easy-to-clean fender. Since it contains no stuffing material, the present fender is virtually indestructible. The lightweight and non-sinkability characteristics of this fender make it further desirable. The fender may be made in numerous attractive colors which cannot wear off and do not stain or discolor the hull of the boat. Furthermore, the fender is relatively inexpensive to fabricate. In the drawings, I have illustrated a present preferred embodiment of my invention, in which:

Figure 1 is a plan view of the plastic boat fender;

Figure 2 is a cross section of the fender taken on plane II—II of Figure 1;

Figure 3 is a view similar to Figure 2 but illustrates a modification thereof;

Figure 4 is an end view of the fender shown in Figure 2;

Figure 5 is an end view of the modified fender shown in Figure 3;

Figure 6 is an enlarged end section of Figure 2;

Figure 7 is an enlarged end section of Figure 3;

Figure 8 shows a further modification of the fender; and

Figure 9 is a side elevation view of the modified fender illustrated in Figure 8.

A tube of plastic material 9 is cut to desired lengths and holes 10 are cut in the respective ends thereof. The cross section of the plastic tube may be of any desired shape. However, a cylindrical or oval configuration is preferred. The present application shows the fender fabricated from a tube of plastic of circular cross section. A second tube of plastic 11 is cut to the desired lengths, approximately the same length as tube 9, and holes 12 are cut in the respective ends thereof. The tube 11 is of a lesser diameter than the tube 9; however, the difference in the respective diameters may vary depending upon factors to be described hereinafter. The tube 11 is inserted inside the tube 9 and the ends of the two tubes are flattened. The degree of flattening may vary; however, preferably the tubes are brought into a contiguous relationship as shown in Figure 2. Washers 13 are then positioned next to the hole 10 and a fastening

2

means 13a here shown as a grommet, is placed through the washers and the ends are swaged to retain the sides in the flattened condition. An end view of this fender is shown in Figure 4. The grommets are preferably made from brass or similar non-corroding material. Plastic material of sufficient rigidity may also be used. It is apparent that each fender may contain any number of grommets spaced along its length or at each end. Preferably the fastening means are hollow as shown; however, solid means may be used.

A modification of the above fender is shown in Figure 3 in which the inside tube 14 is cut to a length less than the length of the outside tube 9. The tube 14 is inserted inside the tube 9, the ends are flattened and fastening means are affixed thereon, as described above. The inside tube 14 is held in a fixed position within the outside tube by frictional contact along surfaces 15. Figure 5 illustrates an end view of this fender.

A further modification is shown in Figure 8 in which only one end of the fender is flattened. The end 16 is not flattened and thus remains open. The end 17 is flattened by use of grommets or similar means as described above. A further modification of the fenders is shown by the use of a rope 18 used to maintain the end 20 of the fender in a flattened condition. It is not necessary to use grommets of any kind to protect the plastic or retain the end in flattened condition when the rope is used. However, to avoid any tendency of the plastic material to tear, it is desirable to insert grommets in 25 each hole in the plastic tube or tubes. The rope maintains the end in flattened condition by being fastened in a small loop through the holes. The use of a rope to retain one end of the fender in flattened condition may be applied to either a single tube or a double tube 30 fender.

The above described fenders are self-draining of water or other liquid since one or both ends are open as shown by the openings 19 in Figures 4 and 5. However, it is possible to seal the ends of the fender by means of heat, 40 solvent or mechanically, in order to provide sufficient buoyancy for use of the fender as a mooring float, emergency life-preserver, etc. Preferably at least one end of the fender is left open.

The fender may be manufactured from many materials including rubber, vinyl plastic, cellulosic-type plastic and others. However, polyethylene material seems to offer the most advantages for boat use, particularly since its specific gravity of approximately 0.93 allows it to float on water. Plastic materials do not become water-logged. The fender can be manufactured in any color 45 and either opaque or translucent. The color is integral and goes all the way through the material, thus avoiding a scuffed appearance on the fender. The wall section of the fender varies from $\frac{1}{16}$ " to $\frac{1}{2}$ " (or perhaps even greater) in order to furnish the degree of resilience and impact strength needed. The limitations on the wall thicknesses, and length, width, etc. of the fender are dictated only by industrial economies and ultimate use.

The major advantage of the present fender is that when it is subjected to extreme pressures or forces, it possesses an inner-resilient member 11 to absorb some of the shock. The outer shell 9 possesses sufficient resiliency to cushion slight or medium blows without marring the hull of the boat or ship. However, when the forces become sufficiently great, the outer shell 9 is pushed inwardly, and if the applied force continued to compress the fender, ultimately a split in the side might occur. However, the inner tube 11 becomes operative in resisting the intense shock prior to the time that splitting would occur in the outer shell 9. The overall fender thus possesses an ability to resist slight shocks without marring the article to be protected and also, it resists extremely heavy shocks with-

out splitting. This type fender is very versatile due to its dual capacity. Thus, the difference in diameters between the two tubes of plastic will depend upon their ultimate use and the resiliency and tendency to split in the outer shell 9. If the outer shell is of extreme toughness to resist some of the heavy shocks itself, the inner tube may be of a substantially lesser diameter than the outer tube and thus, would not become operative until extremely excessive forces had been applied to the fender. Conversely, if it is desirable to have the outer tube sensitive to slight shocks and thus of lighter material, the inner tube would have a diameter more closely approaching that of the outer tube to provide quicker reinforcement for severe shocks to avoid splitting the outer tube.

The grommet on the end of the fender is installed in such a manner that contact between it and the protected surface is avoided, even when the fender is considerably compressed. In other words, the grommet is installed below the effective contact surface of the fender as shown in Figures 4 and 5. Thus the surface being protected by the fender is not contacted by the grommets.

After the ends of the fender are flattened, the sides of the tubes of plastic assume a bowed effect as shown at 20 in Figure 1 but the top and bottom of the tube are bulged outwardly as shown by 21 in Figures 2 and 3. This peculiar geometrical shape enhances the ability of the plastic materials to absorb the intense shocks imparted to the fender without splitting the latter. But the overall design of the fender is simple which permits the use of relatively inexpensive polyethylene tubing as a raw material. After the fender is pressed inwardly by extreme pressures, the parts readily return to their original shape. Other fenders slit if stuffed or burst if they contain a sealed air chamber.

The fender may be produced in any desired length or end configuration. Elongated sections of the fender may be used as a protector for piers and piling which boats come in contact with.

While I have described the present preferred embodiment

ment of my invention, it is to be understood that it may be otherwise embodied within the scope of the following claims.

I claim:

5. A boat fender including a first elongated plastic tube, a second elongated plastic tube disposed inside said first tube, at least one end of the first tube being flattened by moving two diametrically opposed points on the end into close relationship with each other, an end of said second tube being clamped within the flattened end of the first tube, and means to retain the first tube in flattened condition.
10. 2. A boat fender described in claim 1 wherein the second tube is shorter than said first tube.
15. 3. A boat fender described in claim 1 wherein both ends of the first tube are flattened.
20. 4. A boat fender described in claim 1 wherein said tubes are the same length.
25. 5. A boat fender described in claim 1 wherein both ends of the first tube are flattened; the sides of the tube are bowed inwardly and the top and bottom of the tube bulges outwardly.
6. A boat fender described in claim 1 wherein grommets pass transversely through the end of the tube to retain it in flattened condition.
